UNITED STATES PATENT OFFICE.

JESSE R. MOLER, OF OAKLAND, CALIFORNIA.

WATER BAG.

Application filed September 7, 1926. Serial No. 133,897.

The present invention relates to improvements in douche bag, and its particular object is to provide a bag of the character described that is particularly intended to satisfy a want for a sanitary douche bag convenient for use while traveling. The principal object of the invention is to provide a bag of the character described that may be conveniently folded and re-folded so as to occupy very little space when placed in a casing. A further object of the invention is to provide a bag of the character described that resembles a lady's hand bag and may be carried about without causing embarrassment. Further objects and advantages of my device will appear as the specification proceeds.

The preferred form of my invention is illustrated in the accompanying drawing in which—

Figure 1 shows my bag flattened out and ready to be folded along suitable lines,

Figure 2 the bag ready for use in side elevation,

Figure 3 the same bag in top plan view, and

Figure 4 a diametrical section taken along line 4—4 of Figure 1.

While I have shown only the preferred form of the invention, I wish to have it understood that various changes or modifications may be made within the scope of the claims hereto attached without departing from the spirit of the invention.

In its preferred form, my bag is made of a flat sheet of rubber or other water impervious material 1, preferably circular in form, and a covering sheet of decorative fabric, such as a cloth 2 placed below the first sheet and having its margin turned over the margin of the first sheet as shown at 3. A string or cord 4 is interlaced with the margins of the two sheets in the manner shown in Figure 1 so that the cord or string alternately appears on top and at the bottom. In the center of the two sheets of material is provided a suitable outlet member, such as the connecting nipple 6 adapted for connection with a rubber tube 7 at the end of which may be provided an insertion piece 8.

When flattened into the form shown in Figure 1, my bag may be readily folded and re-folded in many different ways so as to be reduced to a package of the very smallest dimensions. To use it, a person need only

pick up any desired number of the exposed sections of the cord 4 and the device will automatically assume the form of a substantially conical pouch as illustrated in Figures 60 2 and 3. The cord may be suspended from any suitable support 9. It will be seen that when carried in the manner shown in Figure 2, with the decorative cover on the outside of the impervious material, the bag entirely loses its identity and may be freely carried from place to place in the same manner as any lady's hand bag. The tubing, of course, will be detached while the device is being carried.

The covering sheet or layer 2 will of course be of less elasticity than is the impervious sheet or layer 1, with the result that when the bag is being used the stresses due to the weight of the water and of the 75 tubing will be borne almost entirely by the sheet 2. By this construction, the covering sheet forms a reinforcement for the impervious sheet, which makes it possible to form the impervious sheet of softer and 80 thinner material than would otherwise be necessary.

I claim:

1. A water bag consisting of a single flat sheet of flexible, water-impervious material, 85 an outlet member secured to said sheet, and means for suspending said sheet in water-retaining position.

2. A water bag comprising a flat sheet of flexible, water-impervious material, a connecting nipple secured to said sheet to form an outlet member, and a cord interlaced with the periphery of the sheet for suspending it in water-retaining position.

3. A water bag comprising a flat sheet of water-impervious material, means for suspending said sheet in water-retaining position, and a flexible conduit connected adjacent the center of said sheet for dispensing the water contained in said sheet.

4. A liquid container comprising a flat, circular sheet of flexible, impervious material, an outlet member secured to said sheet, a cloth covering attached to said sheet, and means engaging the periphery of said sheet 105 for suspending it in liquid-retaining position.

5. A water bag comprising a flat sheet of flexible water-impervious material, a flat sheet of decorative fabric overlying said 110 first mentioned sheet, a connecting nipple secured to the centers of both said sheets,

and means engaging the peripheries of said sheets for suspending them in water-retaining position.

6. A water bag comprising a flat sheet of elastic, water-impervious material, a covering sheet of less elasticity than said first mentioned sheet, the two sheets being secured together, an outlet member secured to both said sheets, and means for suspending

10 said sheets in water-retaining position.

7. A water bag comprising a layer of

elastic, water-impervious material, a covering layer of less elasticity than the first mentioned layer, the two layers being secured together, an outlet member secured to both 15 said layers, and means engaging both said layers for suspending them in water-retaining position.

In testimony whereof I do hereby affix my signature.

JESSE R. MOLER.
